(57) **CLAIM**

The ornamental design for a cowling for an outboard motor, as shown and described.

DESCRIPTION

FIG. 1 is a rear right perspective view of a cowling for an outboard motor showing our new design;

FIG. 2 is a front left perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines in the drawings illustrate portions of the cowling for an outboard motor that are not part of the claimed design.
